UNITED STATES PATENT OFFICE.

ROBERT J. BARKLEY, OF CHANUTE, KANSAS.

DESIGN FOR A CARTON FILLER.

SPECIFICATION forming part of Design No. 29,299, dated September 6, 1898.

Application filed July 30, 1898. Serial No. 687,361. Term of patent 14 years.

To all whom it may concern:

Be it known that I, ROBERT J. BARKLEY, of Chanute, in the county of Neosho and State of Kansas, have invented and produced 5 a new and original Design for a Carton Filler, of which the following is a full, clear, and exact description.

Reference is to be had to the accompanying drawing, forming a part of this specification, 10 and which represents a perspective view of the design.

The design consists in a filler presenting features as follows: The appearance of series 15 of panels *a* equally spaced from each other.

The panels *a* extend transversely of two longitudinal members *b*, which are disposed in proximity to each other and extend across the central portions of the panels *a*, whereby narrow elongated openings *c* appear between the members *b*, extending lengthwise between 20 adjacent panels *a a*.

I claim—

The design for a carton filler substantially as herein shown and described.

ROBERT J. BARKLEY.
